SLIDE TRAY

Richard J. Olson, Lima, and Frank A. Zagara, Rochester,
N.Y., assignors to Eastman Kodak Company, Rochester,
N.Y., a corporation of New Jersey

Filed Dec. 22, 1961, Ser. No. 68,026

Term of patent 14 years

(Cl. D61—1)

Fig. 1

Fig. 2

FIG. 3

FIG. 4

FIG. 6

FIG. 5

FIG. 7

FIG. 8

FIG. 1 is a top plan view of a slide tray showing our new design;

FIG. 2 is a bottom plan view thereof, showing downwardly extending cylindrical-peg gear teeth on the bottom flange;

FIG. 3 is a side elevational view thereof;

FIG. 4 is a fragmentary side elevational view thereof, showing a modified form wherein the gear teeth are of the crown configuration and extend radially from the edge of the bottom flange;

FIG. 5 is a bottom plan view of FIG. 4;

FIG. 6 is a fragmentary side elevational view thereof, showing another modified form wherein the gear teeth are of the crown configuration and extend downwardly from the tray's bottom flange;

FIG. 7 is a bottom plan view of FIG. 6; and

FIG. 8 is a fragmentary cross-sectional view of the slide tray taken on line 8-8 of FIG. 1.

The dominant features of our design are shown in solid lines in the drawing, and reside in the combination on the cylindrical slide tray shown of a plurality of vertical radially-disposed slide compartments notched to facilitate slide handling, an annular slide-retaining ring at the circumference of a central opening extending the full

depth of the tray, and a beveled gear-bearing peripheral base flange. The broken line showing of a slide aperture and slide tray mounting means in the bottom of the tray is for illustrative purposes only.

We claim:

The ornamental design for a slide tray, as shown and described.
